UNITED STATES PATENT OFFICE

161,408

BILLIARD TABLE OR THE LIKE

Robert I. Anderson and Bert Hoeker, Muskegon, Mich., assignors to The Brunswick-Balke-Colender Company, Chicago, Ill., a corporation of Delaware

Application December 22, 1949, Serial No. 6,772

Term of patent 14 years

(Cl. D34—3)

To all whom it may concern:

Be it known that we, Robert I. Anderson and Bert Hoeker, both citizens of the United States and both residents of Muskegon, in the county of Muskegon, State of Michigan, have jointly invented a new, original, and ornamental Design for a Billiard Table or the like, of which the following is a specification, reference being had to the accompanying drawing, forming a part hereof.

In the drawing:

Fig. 1 is a perspective view of a billiard table or the like, showing our new design.

Fig. 2 is a side elevational view thereof.

Fig. 3 is an end elevational view looking at the left end of Fig. 2.

Fig. 4 is an end elevational view looking at the right end of Fig. 2.

We claim:

The ornamental design for a billiard table or the like, as shown and described.

ROBERT I. ANDERSON,
BERT HOEKER,
